METHOD AND MEANS OF IMPRESSING
BRONZE DESIGNS

Paul Louis Graupner, Kotzschkenbroda, Germany,
assignor to "Universelle" Cigarettenmaschinen-
fabrik J. C. Mueller & Co., Dresden, Germany

Application April 6, 1935, Serial No. 15,009
In Germany December 22, 1934

3 Claims. (Cl. 101—178)

This invention relates to the art of printing, and has for an important object thereof the provision of means and an improved method for impressing bronze characters or designs on paper used in the production of cigarettes.

Another object of this invention is to provide a means whereby bronze or like powder may be applied to a paper strip or sheet in a manner whereby the color material will adhere to the paper in an even manner and will not readily wipe off on account of handling of the paper.

A further object of this invention is to provide a method and means for applying a powder color to a paper in a manner whereby the color will be maintained on the paper so that the subsequent movement of the printed paper through a cigarette machine will not effect a clogging of the machine by reason of the powder color used in impressing the character or object on the paper being wiped or otherwise removed from the paper.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a detail side elevation of a printing machine embodying this invention, the operating features of the invention being shown diagrammatically.

Figure 2 is an enlarged side elevation of the impressing means used with the machine disclosed in Fig. 1.

Figure 3 is a fragmentary plan view of the paper strip having characters or designs printed thereon in accordance with this invention.

Referring to the drawings, the letter Z designates a sheet of paper or like flexible material, and in the present instance the paper Z is of a character similar to that used in the production of cigarettes. Heretofore attempts have been made to print or otherwise impress letters, characters or designs upon a sheet or strip of paper, but as this must be done prior to the rolling of the cigarettes, the powdered color which is in a dry state when applied will not satisfactorily adhere to the paper, and the rubbing off of the powder seriously affects the operation of the cigarette machine. At the same time, when the cigarette is finally completed the indicia, design or the like is damaged.

This strip of paper Z is attached at one end to a supply roll R as shown in Figure 1 and may first pass through a printing means, generally designated as P at which point any suitable matter may be printed upon the sheet Z with a liquid or paste-like ink.

After passing through the printing means P

the sheet Z is trained over an idling roller 11 and then passed over a drum 10 which is rotatably carried by a shaft 31. The shaft 31 is mounted on one end of a rock arm 32 pivoted as at 33. A driven gear 28 mounted on a shaft 9 is disposed adjacent the drum 10, and this shaft 9 has mounted thereon a printing cylinder or member 8. This printing cylinder or member 8 has a suitable printing surface carrying the desired indicia, design or character which may be impressed upon the surface of the sheet Z.

A second printing cylinder 17 which is mounted on a shaft 18 is mounted in a position for engagement with the sheet Z and is disposed adjacent a second impression cylinder 12 carried by a shaft 13. The shaft 13 is mounted on one end of a second rock lever 14 which is rockably mounted on a shaft 15.

A driving gear 25 is mounted on a shaft 24 and may be connected to a suitable source of power supply. A gear 26 is mounted on a shaft 18 and meshes with the gear 25, and a driven gear 28 is mounted on the shaft 9. Rotation of the gear 28 is effected through a gear 27 which meshes with the gear 26 and the gear 28.

In accordance with the present method and means of placing indicia, characters or designs upon the sheet Z, a reservoir 1 which is adapted to contain cementitious material in liquid form is mounted in a position whereby the cementitious material may be removed from the reservoir by a drum 2, the periphery of which extends into the reservoir. A transfer drum or roller 4 is mounted on a rock arm 3 and is adapted to contact at timed intervals with the supply drum 3 or roller 2.

The cementitious material on the transfer roller or drum 4 is transferred to a grinding roller or drum 5 which is mounted on a bracket 36.

The cementitious material on the transfer member 5 is smoothed by a counter-roller or drum 6 also carried by the bracket 36 and the periphery of which contacts with the drum 5. A transfer roller 7 is also carried by the bracket 36 in spaced relation to the counter-roller 6 and is disposed in the path of the movement of the printing cylinder or member 8. Adjustment of the bracket arm 36 may be had by means of a thumb screw 37 so that the proper contact of the transfer roller 7 may be had with the impression cylinder 8.

In the present instance the reservoir contains a mucilage or like cementitious material, and the impression made upon the sheet by the impression cylinder 8 is similar to the impression made upon the sheet Z by the powder color printing cylinder 17, although the size of the impression made by the cylinder 8 is larger than the size of the impression made by the cylinder 17.

17. By reason of the larger impression made by the cylinder 8 any slight excess of powder carried by the printing cylinder 17 will adhere to the sheet Z, and this larger base impression will permit slight variance in the positioning of the impressions, so that if the impressions are slightly out of register all of the powder impressed upon the sheet Z by the cylinder 17 will stick to the sheet Z.
- 10 18. A powder or color reservoir 23 is mounted adjacent the cylinder 17, and a transfer drum or cylinder 20 mounted on a shaft 21 extends into the reservoir 23 and has the surface thereof disposed in a position for contact with the printing cylinder 17. Preferably the shaft 21 is carried by the side walls of the reservoir 23, and the position of the transfer drum 20 relative to the printing cylinder 17 is controlled by means of an adjusting screw 33. The reservoir 23 also 15 carries a shield 40 disposed beneath the drum 20 and between this drum 20 and the top of the sheet Z so that none of the powder on the surface of the transfer drum 20 will drop onto the surface of the sheet Z.
- 20 19. Adjustment of the rock arm 32 is effected by means of an adjusting screw 35 which engages the arm 32 adjacent the end opposite from the shaft 31, and a spring 34 holds the end of the arm 32 in contact with the screw 35. In like manner the rock arm 14 is adjusted by means of an adjusting screw 16 which engages the arm 14 at the end opposite from the shaft 13, and a spring 30 maintains the arm 14 in contact with the adjusting screw 16.
- 25 20. In accordance with the method and means hereinbefore described, the mucilage or cementitious material is first applied to the face of the sheet Z, and the impression made by the base printing cylinder 8 is slightly larger than the impression made by the color printing cylinder 17. When the driving gear 24 is rotated a rotation of the gear 26 is effected, and likewise rotation of the gear 28 through the gear 27. Preferably the gears 26, 27 and 28 are of the same size so that 30 the cylinder 8 will rotate at the same speed as the cylinder 17.
- 25 21. As the printing surface of the cylinder 8 contacts with the transfer cylinder or roller 1 a transfer of the mucilage or cementitious material is effected, and when the printing surface of the cylinder 8 contacts with the surface of the sheet Z the impression in mucilage or cementitious material will be made. While this cementitious material is still soft the color cylinder 17 will 35 impress the colored powder upon the surface of the mucilage or cementitious material. Preferably the transfer drum or roller 20 is rotated through the medium of a gear 19 mounted on the shaft 18 which meshes with a gear 22 mounted on the shaft 21, and the ratio of the gears 19 and 22 is such that the linear movement of the surface of the transfer roller 20 is substantially the same as the linear movement of the periphery of the printing cylinder 17.
- 40 22. After the proper color has been impressed upon the sheet Z it may be re-rolled upon a supply roll or passed directly into the cigarette machine, the details of which form no part of the present invention. In Figure 3 there is disclosed a sheet Z upon which the base impression 38 has been impressed, and upon this base impression a top or

color impression 41 has been made by the powdered color material 41 contained in the reservoir 23. It will be here noted that the base impression is slightly larger than the color or top impression so that any over-running powder will be 5 retained on the sheet Z and not permitted to drop off or be rubbed off during the movement of the sheet Z through the cigarette machine.

It is obvious that various changes and modifications may be made in the method hereinbefore 10 described and in the details of construction and design of the above embodiment without departing from the spirit thereof or the scope of the appended claims.

What is claimed is:

1. A means for placing powdered color impressions on a web comprising a base printing cylinder, a color printing cylinder, means for rotating each of the cylinders in unison, a pair of impression rollers disposed one adjacent each cylinder and contacting therewith, means for swingably supporting said impression rollers for contact one with each cylinder, said rollers having the web trained thereover, means for elastically tensioning said supporting means to bias 25 the said rollers against the cylinders, means for placing a mucilaginous substance on the base cylinder for impression on the sheet, and means contacting with the color cylinder for placing a powdered color thereon, said color cylinder being so timed with respect to said base cylinder whereby the powdered color on the color cylinder will be impressed on the mucilaginous impression. 30

2. A means for placing powdered color impressions on a web comprising a base printing cylinder, a color printing cylinder, means for rotating the cylinders in unison, a pair of impression rollers disposed one adjacent each cylinder, a lever support for each of said rollers pivoted to support the roller swingably, a spring attached to each of said levers biassing it to swing to place an impression roller against a cylinder, said rollers having the web trained thereover, means for placing a mucilaginous substance on the base cylinder for impression on the web, and means contacting with the color cylinder for placing a powdered color thereon, said cylinders being timed to superimpose the color on the base impression. 45

3. A means for placing powdered color impressions on a web comprising a base printing cylinder, a color printing cylinder, means for rotating the cylinders in unison, a pair of impression rollers disposed one adjacent each cylinder, a lever support for each of said rollers pivoted to support the roller swingably, a spring attached to each of said levers biassing it to swing to place an impression roller against a cylinder, an adjustable swing limiting means for each lever to fix the extent of movement of the impression roller towards the cylinder, said rollers having the web trained thereover, means for placing a mucilaginous substance on the base cylinder for impression on the web, and means contacting with the color cylinder for placing a powdered color thereon, said cylinders being timed to superimpose the color on the base impression. 55

PAUL LOUIS GRAUPNER. 70
